UNITED STATES PATENT OFFICE.

EDMUND J. Y. HAMMETT, OF LANSDALE, PENNSYLVANIA.

SMOKER'S ARTICLE.

Application filed April 14, 1923. Serial No. 632,027.

To all whom it may concern:

Be it known that I, EDMUND J. Y. HAMMETT, a citizen of the United States, residing at Lansdale, county of Montgomery, 5 and State of Pennsylvania, have invented a certain new and useful Improved Smoker's Article, of which the following is a specification.

This invention, generally stated, relates 10 to ash-trays as used by smokers and has more particular relation to that type provided with cigarette-choker devices.

The leading object of the present invention is to provide a simple, efficient and comparatively inexpensive ash-tray provided 15 with cigarette-choker equipment possessed of novel characteristics in that the parts may be readily taken apart for cleaning purposes; a continuous choker compartment 20 is present in contradistinction to spaced apertures; and clogging of choker-apertures is eliminated. A further object resides in the provision of general details of construction and arrangement and combination of 25 parts for attaining the results sought by said leading object.

The invention consists of the improvements hereinafter described and finally claimed.

30 The nature, characteristic features and scope of the invention will be more fully understood from the following description taken in connection with the accompanying drawings forming part hereof, and in which:

35 Fig. 1, is a top or plan view of a device embodying features of the invention.

Fig. 2, is a view, principally sectioned, 40 illustrating the manner of assembling the various parts.

Fig. 3, is a fragmentary view in section of the part assembled but showing a modified form of attaching means.

45 Fig. 4, is a similar view illustrating a further modified form of attaching means.

Fig. 5, is a similar view, drawn to an enlarged scale, illustrating a modified form of tray construction, and

Fig. 6, is a fragmentary view in section illustrating another form of tray construction.

For the purpose of illustrating my invention I have shown in the accompanying drawings several forms thereof which are at present preferred by me, since the same have been found in practice to give satis-

factory and reliable results, although it is to be understood that the various instrumentalities of which my invention consists can be variously arranged and organized 60 and that my invention is not limited to the precise arrangement and organization of the instrumentalities as herein shown and described.

In the drawings and referring more particularly to Figs. 1 and 2, 10 designates a dish-shaped receptacle, which in practice is stamped, spun or cast from metal, although other material may be employed as for instance glass. Fixed to and rising from the bottom of receptacle 10 is a stud 11 the 65 upper end of which is screw-threaded at 12. The receptacle 10 is provided with an annular, flat, horizontally extended rim 13. The annular wall of receptacle 10 as extending from the receptacle bottom to rim 13 is inclined in an outwardly extending direction as at 14, the juncture of wall 14 with the receptacle bottom forming an acute angle. Adapted to seat within receptacle 70 10, in nested relation therewith, is a part which functions in three capacities. It completes a cigarette-choker channel, forms an ash-receiver and serves as a support for a match-box holder. In practice it is also

75 stamped, spun or cast from metal although glass or other material may be employed. It consists of a dished portion 15 having a central, tapered upwardly extended member 16 and an annular, inclined outwardly extending skirt 17. The bottom edge of skirt 17 rests upon the bottom of receptacle 10 and fits snugly against the wall 14 of said receptacle. In cross-section there is thus 80 provided a substantially V-shaped channel 18 of annular, continuous formation to provide a cigarette-choker. The juncture of skirt 17 with the wall of dished portion 15 is flush with rim 13 of receptacle 10 to 85 provide a cigar or cigarette rest. The part 15 forms an ash-receiver and the part 16 which extends in a plane above rim 13 of receptacle 10 is apertured as at 19 to permit penetration of the threaded end 12 of stud 11. 90 20 designates a match-box holder the lower end of which is provided with a foot 21 interiorly screw-threaded for cooperatively engaging with the screw-threaded end of stud 11 to lock the above described parts together. The top of part 16 is flat 95 and foot 21 seats thereon. It is thus apparent that the parts may be readily taken

apart for cleaning purposes. I am aware that cigarette-chokers comprised of spaced apertured portions have been heretofore used but in such devices not only do the cigarette receiving spaces become clogged, thus necessitating probing to clear such apertures, but the number of cigarettes which may be accommodated is limited. In my device not only is the choker channel 10 continuous thus accommodating many cigarettes but clogging thereof is eliminated since an implement may be readily moved around the annular channel to dislodge any obstructions. Further the device may be 15 readily taken apart for cleaning purposes.

The construction shown in Fig. 3, is similar in all respects to that above described with this exception, that, the means of attaching the parts in assembled position comprises a ball and socket connection instead of the parts 11, 12, 21. Fixed to the bottom of receptacle 10 is a socket formed with yielding or spring fingers 22. Fixed to the bottom of foot 21 of match-box holder 20 is a stem 23 for passage through opening 19 of part 16, said stem terminating in a ball for cooperatively engaging within the spring fingers 22.

In Fig. 4, a bayonet-joint connection is employed for interlocking the parts. The 30 receptacle 10 has fixed to the bottom thereof a socket 24 the side wall of which is provided with a slot or groove shaped to cooperatively receive a pin fixed to a stem 25 carried by foot 21 of the match-box holder 20, whereby 35 after introducing said stem within said socket a slight twist of the match-box holder will cause stem 25 to interlock with socket 24.

Referring now to Fig. 5, a two-piece construction is shown instead of a three piece construction. In other words the receptacle and dished parts illustrated in Figs. 1, 2, 3 and 4 are formed as an integral structure mounted upon which is the match-box 45 holder 20. 26 designates the ash-receiver and 27 the cigarette-choker channel. By making the walls 28-29 so that they converge toward the bottom of the article the V-shaped, continuous, annular channel is 50 provided as in Figs. 1, 2, 3 and 4. Foot 21 of the match-box holder is provided with a screw-threaded stem 30 for passage through opening 19' of part 16', a nut 31 being provided to secure these parts together.

Fig. 6, also shows a two-part construction 55 but the part 16' shown in Fig. 5, is omitted to provide an enlarged ash-chamber 32. Match-box holder 20 in this construction is supported upon a bowed strap 33 supported upon the flat rim 13.

It will now be apparent that I have devised a novel and useful construction which embodies the features of advantage enumerated as desirable in the statement of the invention and the above description and 60 while I have in the present instance shown and described the preferred embodiments thereof which have been found in practice to give satisfactory and reliable results, it is to be understood that the same are susceptible of modification in various particulars without departing from the spirit or scope of the invention or sacrificing any of its advantages.

What I claim is:

1. In a device of the character stated a receptacle of thin metal having an annular, outwardly and upwardly extended wall terminating in a flat rim extended beyond the receptacle proper, a central ash-receiving part having an outwardly extended skirt seated within the receptacle said wall and skirt providing an annular continuous choke-channel of V-shaped cross-section and also providing a cigar or cigarette support, the 85 juncture of said ash-receiving part and skirt being in the same plane with said rim.

2. In a device of the character stated a receptacle of thin metal having an annular, outwardly flared wall, terminating in a flat rim extended beyond the receptacle proper, a central ash-receiving part having a central apertured portion extended above said receptacle top and having an outwardly flared skirt, said skirt and wall forming an annular continuous choke-channel of substantially V-shaped cross-section when said parts are in nested relation and also providing a cigar or cigarette support, a stud carried by said receptacle bottom and extended upwardly through said central apertured portion and a match-box holder seated upon said central portion and cooperatively engaging said stud to interlock the parts.

In testimony whereof, I have hereunto signed my name.

EDMUND J. Y. HAMMETT.
